Primary Examiner — Susan Moon Lee(74) *Attorney, Agent, or Firm* — I. Michael Bak-Boychuk(57) **CLAIM**

I claim the ornamental design for a beehive honey comb suspending frame, as shown and described.

DESCRIPTION

FIG. 1 is a top view of a beehive honey comb suspending frame showing my claimed design;

FIG. 2 is a front view of a beehive honey comb suspending frame showing my claimed design, the rear view being the mirror image thereof;

FIG. 3 is a bottom view of the beehive honey comb suspending frame;

FIG. 4 is a first end view of the beehive honey comb suspending frame, the second end view being the mirror image thereof;

FIG. 5 is a perspective view of the beehive honey comb suspending frame; and,

FIG. 6 is a sectional view of the beehive honey comb suspending frame taken along line 6—6 of FIG. 5.
